UNITED STATES PATENT OFFICE

2,447,695

TERMINAL CHECK FOR MECHANICAL LUBRICATORS

Bengt E. Folke, Mamaroneck, N. Y., assignor to Nathan Manufacturing Company, New York, N. Y., a corporation of New York

Application June 12, 1944, Serial No. 539,935

1 Claim. (Cl. 184—36)

1
This invention relates to terminal checks to be used in connection with a mechanical lubrication system where minute amounts of oil are metered out by the mechanical lubricator in proportions as needed.

In a system of this nature employing a terminal check of the type disclosed, when the oil is delivered for the purpose of lubricating, for example, a steam engine where the pressure of the steam fluctuates from time to time, it is necessary that some form of terminal check be located where the oil enters a steam passage. This terminal check must serve to maintain the oil pressure in the line between the lubricator and the terminal check at a constant pressure irrespective of pressure fluctuations of the steam. It is important that a terminal check of this type be arranged to prevent steam or condensation from finding its way back to the lubricator through the oil pipes.

It is the principal object of the invention to provide means in a terminal check permitting pressure adjustment within a limited range and to prevent pressure regulation below a predetermined minimum.

Another object is to provide means whereby the pressure setting of the check may be easily adjusted.

Other objects and advantages will become apparent in the following specification and accompanying drawing.

10 is a valve casing having a threaded inlet connection **11** for oil from a mechanical lubricator, an inlet passage **12**, a threaded outlet **13**, and a discharge passage **14** for the oil. The communication between the inlet passage **12** and the discharge passage **14** is controlled by a valve member **15** acting upon a valve seat **16** screwed into the casing **10**.

The valve **15** is held in position by means of a threaded guide **17**, a spring **18**, and an abutment **19**. The spring **18** serves to hold the valve **15** against the top of the abutment **19** without lost motion.

A diaphragm **20** is clamped between the threaded guide **17** and the abutment **19**. At its outer periphery the diaphragm **20** is clamped between the casing **10** and a ring **21** held in position by a housing **22**. The diaphragm is supported by a loosely fitting flexible plate **23**.

A large coiled spring **24** exerts a predetermined force on the abutment **19** and the valve **15**, holding the valve against its seat **16**. A supplementary coiled spring **25**, disposed within the coils of spring **24**, exerts additional force against

2
the abutment **19** and the valve **15**. The tension of the spring **25** can be adjusted by means of a regulating screw **26** locked in position by a lock nut **27**. An extension rod **28** of the regulating screw **26** provides a guide for the supplementary spring **25** substantially throughout its length. The lower end of spring **25** is guided by a cylindrical extension of abutment **19**.

The operation of the terminal check is as follows:

Oil from the lubricator enters the inlet passage **12** and fills the chamber below the flexible diaphragm **20**. As additional oil is pumped by the lubricator into the chamber through the inlet passage **12**, the pressure rises until finally it overcomes the resistance of the springs **24** and **25** and flexes the diaphragm upwardly, at the same time lifting the valve **15** from its seat **16** and permitting oil to be discharged through the passage **14** until the pressure below the diaphragm **20** balances the spring pressure on top of the diaphragm, at which time any further reduction in pressure will again permit the valve **15** to close and seat against the valve seat **16**.

The pressure at which the valve **15** will open and close can be adjusted by means of the regulating screw **26**. It will be noted, however, that even though the regulating screw **26** were screwed up far enough to relieve all tension on the spring

30 **25**, the spring **24** would still exert pressure on the abutment **19** and the valve **15**, the tension of the spring **24** being constant and independent of the regulating screw **26**. The regulating screw **26** permits increasing the pressure at which the

35 valve **15** will open but does not permit decreasing the pressure below a certain predetermined minimum, namely that which the spring **24** exerts against the valve. The tension of the spring **24** is made sufficiently great so that the terminal

40 check will operate without damage to itself or its associated devices even though, through carelessness or for any other reason, the tension of the supplementary spring **25** had been entirely relieved.

45 It will also be noted that the force required to adjust the regulating screw **26** is relatively small as only part of the load is carried by the supplementary spring **25**, and only the force exerted by the spring **25** need be overcome by the regulating

50 screw **26**. The spring **24** exerts pressure directly against the housing **22** and does not transfer any of its pressure to the regulating unit. Attention is also drawn to the fact that the regulating screw **26** comes to a stop at the outside of the housing by abutting lock nut **27**, while the lower

end of extension rod 28 of screw 26 is still slightly spaced from the cylindrical extension of abutment 19. It is impossible therefor to compress the auxiliary spring to such an extent that it would keep valve 15 closed. This results in a fool proof construction inasmuch as it prevents adjustment of the spring 25 beyond a predetermined tension by unauthorized manipulation of the screw, thus leaving the terminal check always in an operative condition.

While I have shown a preferred construction of the terminal check, it is obvious that many changes in the form, proportion, combination of parts and minor details of construction may be resorted to without departing from the principles or sacrificing any of the advantages of the invention, as defined in the appended claim.

What I claim as new is:

In a terminal check for mechanical lubricators, a casing having a chamber with an inlet and an outlet, a flexible diaphragm forming one of the walls of said chamber, an abutment having a cylindrical extension fastened to said diaphragm, a valve member within said abutment adapted to control said outlet, a spring housing secured to said casing adapted to hold said diaphragm within said casing, said housing having a fixed inner shoulder, a coiled heavy main spring of predetermined tension within the housing disposed between said shoulder and said abutment exerting a relatively high pressure against the abutment to urge said valve member to a position closing said outlet, an auxiliary coiled light spring within the housing disposed within the coils of said main spring and bearing against

10 said abutment, the lower end of said auxiliary spring disposed around said cylindrical extension, and a screw through said housing and bearing against the upper end of said auxiliary spring for adjusting the tension of said auxiliary spring from the exterior of the housing to increase the pressure against said valve member over that exerted by said main spring, said screw having an extension rod projecting into the housing disposed within said auxiliary spring and coaxial with said cylindrical extension for guiding said auxiliary spring substantially throughout its length, said screw adapted to come to a stop exteriorly of the housing leaving a slight clearance 15 between the ends of said extension rod and said cylindrical extension of the abutment to prevent the screw from compressing said auxiliary spring beyond a predetermined tension.
